(57) **CLAIM**

The ornamental design for a cookware vessel, as shown and described.

DESCRIPTION

FIG. 1 is a top perspective view of a cookware vessel according to the new design;

FIG. 2 is a bottom perspective view of the cookware vessel shown in FIG. 1;

FIG. 3 is a top view of the cookware vessel shown in FIG. 1; FIG. 4 is a bottom view of the cookware vessel shown in FIG. 1;

FIG. 5 is a side elevation view of the cookware vessel shown in FIG. 1;

FIG. 6 is an opposite side elevation view of the cookware vessel shown in FIG. 1;

FIG. 7 is a left end view of the cookware vessel shown in FIG. 1;

FIG. 8 is a right end view of the cookware vessel shown in FIG. 1;

FIG. 9 is a cross-sectional view taken along the line 9-9 of the cookware vessel shown in FIG. 3;

FIG. 10 is an enlarged cross-sectional view taken along the line 10-10 of the cookware vessel shown in FIG. 5; and,

FIG. 11 is an enlarged cross-sectional view taken along the line 11-11 of the cookware vessel shown in FIG. 5.

In the drawings, the broken lines form no part of the claimed design.

1 Claim, 9 Drawing Sheets
